CAN OPENER-HANDLE COMBINATION

George W. Anderson, Great Neck, N. Y.

Application April 6, 1950, Serial No. 154,219

5 Claims. (Cl. 30—123)

1

This invention relates to a combination can opener and handle and it particularly relates to a combination can opener and handle useful for the dispensing and consumption of fruit juices and liquid beverages.

It is among the objects of the present invention to provide a convenient, readily manufactured, compact, easily manipulated combined handle and can opener which may be readily handled by the housewife or other member of the household to open cans of fruit juices and carbonated beverages such as beer, and at the same time provide a handle, enabling ready dispensing or consumption thereof.

It is another object of the present invention to provide an inexpensive, relatively small, light weight implement capable of mass production for utilization and opening and carrying beverage and fruit juice cans, which may be distributed as a premium or in connection with or to enhance the sales of various types of fruit juices and liquid beverages.

Still further objects and advantages will appear in the more detailed description set forth above, it being understood, however, that this more detailed description is given by way of illustration and explanation only and not by way of limitation, since various changes therein may be made by those skilled in the art without departing from the scope and spirit of the present invention.

In accomplishing the above objects, it has been found most suitable, according to one embodiment of the present invention, to provide an approximately U-shaped, relatively stiff metal bar which may be readily stamped out in one or two operations and formed into the desired shape and size, which will enable ready application to and opening of a can and at the same time which will enable ready attachment to such can to be used as a pouring handle or as a handle to enable ready manipulation of the can or drinking of the beverage therefrom.

In the preferred form, the can opening top is provided with a double claw pivotally connected to the can B, which supports the opener in the pivotal movement thereof for opening the top of the can.

At the same time the can opening portion is provided with a down-turned abutment to ride against the bead at the top of the can when the opener is used as a handle. The other end of the opener is so shaped and provided with an inturned portion that it may be snapped under the bottom bead or opposite bead to enable con-

2

venient handling and carrying of the can for drinking or pouring purposes.

With the foregoing and other objects in view, the invention consists of the novel construction, combination and arrangement of parts as hereininafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

15 Fig. 1 is a side elevational view partly in section, showing a can with the can opener mounted thereon to open the top thereof, the opener being shown in the position it would be after the top has been opened, with the dot-and-dash line position showing the initial position of the opener before the can-opening movement.

Fig. 2 is a side elevational view partly in section, of a can with the combined can opener and holder and handle combination of the present invention applied thereto.

Fig. 3 is a top elevational view of the can opener of the present invention in the position shown in Fig. 2.

Fig. 4 is a front elevational view of the can opener of the present invention, showing the inside view of the can opening in the position shown in Fig. 2 before attachment to a can.

Referring to Figs. 1 to 4, there is shown a can A and an opener B. The opener B has the top can-opening portion C and the bottom can-engaging portion D.

As shown in Figs. 1 to 4, the can opener takes the approximate form of a U with a base 10 and an upper leg 11 and a bottom leg 12.

40 The upper leg 11 terminates in a pointed element 13 having a cutting nose 14 with the sharp edges 15 which will cut into the top 16 of the can A, leaving the opening 17, the edges of which will be turned downwardly so as to enable direct drinking from the can A if desired.

45 The turned-down portion of the top 16 of the can A is indicated at 18.

The upper leg 11 has the down-turned pivotal claws or hook members 19, which may be stamped out of the same metal and turned downwardly, leaving the shoulders, as for example indicated at 20 in Fig. 3. These claws or hooks have an open space as indicated at 21 and have a contact edge as indicated at 22 to abut the side wall 23 of the can in the position of Fig. 2 and

to swing pivotally upon the upper bead 24, as indicated in Fig. 1.

It will be noted that the base 10 is inclined somewhat at an angle of 90° to the upper leg 11 whereas the lower leg 12 is at an inclination of between 120 to 150° to the base 10, which lends itself to a proper handle construction, as indicated in Fig. 2.

At the end of the leg 12 is the inturned portion 25, which is designed to snap under the lower bead 26 at the bottom 27 of the can A.

Although the device B is made of relatively stiff stock, the resiliency between the legs 11 and 12 in respect to the base 10 will permit the upturned leg 25 to snap under the bead 26 and hold the handle 10 firmly in position.

The leg 12 may also be provided with a conventional cap opener having the opening 28, the camming face 29 and the nose 30 to fit under and lift the cap.

Opposed to the upturned leg 25 is the down-turned stamped-out portion 31 which will abut the upper bead 24, as indicated in Fig. 2, when the handle B is serving to carry the can or enable pouring or drinking of fluid therefrom.

The entire structure of Figs. 1 to 4, may be readily stamped out of metal in one piece and may be inexpensively formed and manufactured, so that it may be distributed as a premium or advertising or sold at relatively low cost.

While there has been described herein a preferred form of the invention, it should be understood that the same may be altered in details and in relative arrangement of parts within the scope of the appended claims.

Having now particularly described and ascertained the nature of the present invention, and in what manner the same is to be preformed, what is claimed is:

1. A combined can opener and handle for beaded cans comprising a U-shaped member having a base, an upper leg and a lower leg, the upper leg having a forwardly-extending triangular shaped opening end section, said upper leg having a central claw member extending rearwardly and two side claw members extending forwardly to engage the can and the lower leg having means to engage the bottom bead of the can to enable the opener to serve as a handle, and said upper leg having an angle of substantially 90° to the base of the U-shaped member and said lower leg having an angle of substantially between 120° and 150° to the base.

2. A combined can opener and handle for beaded cans comprising a U-shaped member having a base, an upper leg and a lower leg, the upper leg having a forwardly-extending triangular shaped opening end section, said upper leg

having a central claw member extending rearwardly and two side claw members extending forwardly to engage the can and the lower leg having means to engage the bottom bead of the can to enable the opener to serve as a handle, the last-mentioned means including a lip to latch under the bottom bead of the can, and said upper leg having an angle of substantially 90° to the base of the U-shaped member and said lower leg having an angle of substantially between 120° and 150° to the base.

3. A combined can opener and handle for beaded cans comprising a U-shaped member having a base, an upper leg and a lower leg, the upper leg having a forward-extending triangular shaped opening end section and the lower leg having means to engage the bottom bead of the can to enable the opener to serve as a handle, the last-mentioned means including a lip to latch under the bottom bead of the can and the upper leg having a lug to latch inside of the upper bead, and said upper leg having an angle of substantially 90° to the base of the U-shaped member and said lower leg having an angle of substantially between 120° and 150° to the base.

4. A combined can opener and handle for cylindrical beer cans with an upper bead and a lower bead comprising a U-shaped heavy sheet metal member having an upper horizontal leg with a downwardly and forwardly inclined triangular cutter portion, a central rearwardly extending lug for pivoting on said top bead and forwardly extending side hook members for fitting under and engaging the outside of the can at the top thereof just under the bead, and said upper leg having an angle of substantially 90° to the base of the U-shaped member and said lower leg having an angle of substantially between 120° and 150° to the base.

5. The opener and handle of claim 4 in which the base of the U-shaped member has an oblique lower extension serving as the other leg, which extension has an upturned end lip to engage under the lower bead of the can.

GEORGE W. ANDERSON.
